UNITED STATES PATENT OFFICE.

HEINRICH WALDES, OF PRAGUE-WRSCHOWITZ, AUSTRIA-HUNGARY.

ADVERTISING DEVICE.

1,116,178.

Specification of Letters Patent. Patented Nov. 3, 1914.

Application filed November 20, 1913. Serial No. 802,050.

To all whom it may concern:

Be it known that I, HEINRICH WALDES, a citizen of the Empire of Austria-Hungary, and resident of Prague-Wrschowitz, Bohemia, Empire of Austria-Hungary, have invented certain new and useful Improvements in Advertising Devices, of which the following is a specification.

The object of this invention is to provide 10 an advertising device adapted to attract the eye and guide the attention of the observer to one of a plurality of items having relation to another item or class of items, the indication of the first item being capable of 18 being changed, with a corresponding change in the indication of the second item or class of items.

The structural embodiment of the invention comprises a plate having thereon a series 20 of panels arranged preferably in an arc, a series of indicator-stations spaced from the series of panels, and a double ended pointer pivoted between the panels and the indicator-stations, so that it may be swung 25 opposite any panel and a corresponding indicator-station. In such embodiment the body of the pointer is concealed by arranging the same behind a portion of the plate, thereby leaving the central portion of the 30 plate open for advertising purposes; and the pointer carries arcuate panels in view of the observer, said pointer panels being between the central display space and the series of panels on the one hand, and on the 35 other hand between the central display space and the indicator-stations. By the means described the entire device has the appearance 40 of a dial and is extremely attractive to the eye and the attention of the observer, and by reason of the change permitted in the position of the pointers and their panels the appearance to the eye is varied and curiosity aroused.

In the accompanying drawing, Figure 1 is 45 a front elevation of a display device embodying the invention, Fig. 2 is a vertical section on line 2—2, Fig. 1, and Fig. 3 is a rear elevation.

Similar reference numerals indicate corresponding parts in each of the figures.

The supporting plate 10 has at its front portion panels 11 and intermediate spaces 12, the latter of which are approximately the same size and shape as the panels. The 55 panels are arranged in an arc at the upper portion of the plate 10, and preferably ar-

ranged radially to the point of pivoting 13 of the pointer. At the lower portion of the plate is arranged a series of indicator-stations 14, also located in an arc, said stations corresponding in number to the panels and the spaces between them. The pointer comprises a main portion 14 at the rear of the plate and pivoted to the latter by any suitable means so as to swing freely thereon, and two panels 15 and 16 respectively supported at the front of the plate 10, and connected with the ends of the rear portion 14 of the pointer through arcuate slots 17 and 18 respectively in the plate. A point 19 projects radially from the panel 15 toward the plate panels 11, and a point 20 projects radially from the panel 16 toward the station-indicators. Between the pointer panels 15 and 16 is arranged on the plate 10 a circular panel 21. The arcuate pointer panels are concentric with this circular panel, and in the operation of the device move concentric therewith between the same and the radial panels of the plate and the indicator-stations respectively. The pointer panels serve to cover a considerable portion of the slots 17 and 18 respectively and add to the effectiveness of the device by thus concealing the means by which the positions of the pointer are changed. On the plate 10 at each side of the same, between the limits of movement of the pointer as determined by the slots, are preferably arranged other radial panels 22 continuing in character the panels 11, so that the plate as a whole has the general appearance of a dial. For increasing the attractive effect upon the eye, the point of pivoting 13 of the pointer is arranged eccentrically within this dial, that is, as shown in Figs. 1 and 3, the point of pivoting is below the center of the plate, whereby those panels at the upper portion of the same are elongated and the panels 22 are of shorter length.

The lower portion of the plate 10 is made in any suitable form so as to provide a base 23. The plate is supported at its rear by a leg 24 hinged at 25 thereto. The device is thereby held upright, and the pointer at the rear of the plate is unobstructed and free to be moved.

In the panels 11 and the spaces between them advertising matter of any desired nature may be placed, and the corresponding indicator-stations, which are diametrically opposite the panels, may have adjacent thereto any desired wording, and whenever by

hand, the pointer is swung so that the point 19 is directed to a different panel 11 or space 12 adjacent the same, the lower point 16 will be moved from one indicator-station to 5 another, corresponding to the movement of the upper part 19. The panels 15 and 16 on the pointer may bear any suitable advertising matter or matter relevant to the plate panels or to the indicator-stations to which 10 the pointer panels are respectively adjacent. A scheme of such use is shown in Fig. 1, in which the indicator-stations are employed for a progressive series of numbers indicating different sizes of snap- 15 buttons used as garment-fasteners, and the upper panels 11 and the spaces between them are employed to receive names of different varieties of cloth for which the snap-buttons are suitable respectively. 20 The pointer panel 15 has the words "For this fabric", indicating thereby whatever fabric the point 19 may at the time denote, and the lower pointer panel 16 has the words "Use this size", which indicates whatever size in the series of snap- 25 buttons corresponds to the particular indicator-station at which the point 20 is located. By swinging the pointer by hand, applied to the panel 15 or 16, the upper 30 point 19 can be brought opposite the particular kind of goods used, and the lower point 20 is thereby correspondingly swung into position opposite that indicator-station showing the proper size of snap-fastener to 35 be used for those goods. The device thereby constitutes an indicator useful in connection with the manufacture of clothing, and in the sale of the snap-fasteners.

One embodiment of the invention is shown 40 and described, but it is obvious that changes

may be made therein without departing from the spirit of the invention.

I claim:

1. An advertising device comprising a dial plate provided with diametrically opposite arcuate slots, with a series of panels disposed adjacent one of said slots concentric therewith, and with a series of indicator stations in corresponding relation to said panels adjacent the other slot and concentric therewith, and a swiveled arm pivoted between said slots underneath said plate and carrying pointers at its opposite ends, said ends extending through said slots and exposed on the upper face of said plate and 50 projecting toward said panels and stations respectively.

2. An advertising device comprising a dial plate provided with diametrically opposite arcuate slots, with a series of panels 60 disposed adjacent one of said slots concentric therewith, and with a series of indicator stations in corresponding relation to said panels adjacent the other slot and concentric therewith, a swiveled arm pivoted between 65 said slots underneath said plate, opposite ends thereof extending through said slots, and exposed on the upper face of said plate, arcuate panels disposed on said ends of said arm, having pointers projecting toward said 70 panels and stations respectively, said plate panels, stations and pointer panels containing indicia.

In testimony that I claim the foregoing as my invention, I have signed my name in 75 presence of two subscribing witnesses.

HEINRICH WALDES.
